US00D971703S

(12) **United States Design Patent** (10) **Patent No.:** **US D971,703 S**
Haddick (45) **Date of Patent:** **** Dec. 6, 2022**

- (54) **HANDHELD AERATION IMPLEMENT**
(71) Applicant: **Brandon Haddick**, Syracuse, UT (US)
(72) Inventor: **Brandon Haddick**, Syracuse, UT (US)
(**) Term: **15 Years**
(21) Appl. No.: **29/739,239**
(22) Filed: **Jun. 23, 2020**
(51) LOC (13) Cl. **08-01**
(52) U.S. Cl.
USPC **D8/1**
(58) **Field of Classification Search**
USPC D8/1, 3, 6, 7, 9, 12, 13
CPC A01C 5/02; A01B 1/16
See application file for complete search history.

(57) **CLAIM**

The ornamental design for a handheld aeration implement, as shown and described.

DESCRIPTION

FIG. 1 is an isometric perspective view of a handheld aeration implement showing my design;
FIG. 2 is a forward view thereof;
FIG. 3 is a rearward view thereof;
FIG. 4 is an enlarged top view;
FIG. 5 is an enlarged bottom view;
FIG. 6 is a left view; and,
FIG. 7 is a right view thereof.

1 Claim, 6 Drawing Sheets
